CLAIM

The ornamental design for a cylindrical pleated air filter with top and sidewall filtering areas, as shown and described.

DESCRIPTION

FIG. 1 is a side elevational view of an air filter showing our new design, the other sides being identical to that shown;
FIG. 2 is a bottom plan view;
FIG. 3 is a top plan view;
FIG. 4 is a perspective view;
FIG. 5 is an enlarged fragmentary sectional view taken along line 5—5 of FIG. 3 ; and,
FIG. 6 is an enlarged fragmentary perspective view showing details of the pleats.
